(57) **CLAIM**

The ornamental design for a solar wall light as shown and described.

DESCRIPTION

FIG. 1 is a front, right, top perspective view of a solar wall light showing my new design;
 FIG. 2 is a back, right, bottom perspective view thereof;
 FIG. 3 is a front view thereof;
 FIG. 4 is a back view thereof;
 FIG. 5 is an enlarged left view thereof;
 FIG. 6 is an enlarged right view thereof;
 FIG. 7 is a top view thereof;
 FIG. 8 is a bottom view thereof;

FIG. 9 is an enlarged view of the encircled area 9 of FIG. 1;
 FIG. 10 is an enlarged view of the encircled area 10 of FIG. 3; and,
 FIG. 11 is an enlarged view of the encircled area 11 of FIG. 8.

The broken lines shown on the drawings depict portions of the solar wall light that form no part of the claimed design.

1 Claim, 11 Drawing Sheets
